US00D923562S

(12) **United States Design Patent** (10) **Patent No.:** **US D923,562 S**
Ensing et al. (45) **Date of Patent:** **** Jun. 29, 2021**

(54) **RECHARGEABLE BATTERY**

- (71) Applicant: **Theragun, Inc.**, Beverly Hills, CA (US)
(72) Inventors: **Geert Ensing**, Shanghai (CN); **Michael Waldron**, Dunnington (GB)
(73) Assignee: **THERAGUN, INC.**, Beverly Hills, CA (US)

(**) Term: **15 Years**(21) Appl. No.: **29/771,836**(22) Filed: **Feb. 25, 2021****Related U.S. Application Data**

- (60) Continuation of application No. 29/715,953, filed on Dec. 5, 2019, now Pat. No. Des. 911,932, which is a division of application No. 29/619,833, filed on Oct. 2, 2017, now Pat. No. Des. 869,387.

Primary Examiner — Christy Nemeth*(74) Attorney, Agent, or Firm* — Jeffer Mangels Butler & Mitchell LLP; Brennan C. Swain, Esq.(57) **CLAIM**

The ornamental design for a rechargeable battery, as shown and described.

DESCRIPTION

FIG. 1 is a perspective view of a rechargeable battery of our new design;

FIG. 2 is a front elevational view thereof;

FIG. 3 is a rear elevational view thereof;

FIG. 4 is a right side elevational view, the left side elevational view being a mirror image thereof;

FIG. 5 is a top plan view thereof; and,

FIG. 6 is a bottom plan view thereof.

The broken lines in the drawings are for the purpose of illustrating portions of the rechargeable battery that form no part of the claimed design.
